UNITED STATES PATENT OFFICE.

CLIFFORD F. RANDOLPH AND CHARLES L. RICARDS, OF PLAINFIELD, NEW JERSEY,
ASSIGNORS TO NILES-BEMENT-POND COMPANY, OF NEW YORK, N. Y., A CORPORA-
TION OF NEW JERSEY.

CLAMPING MECHANISM FOR RADIAL DRILLS.

Application filed February 2, 1922. Serial No. 533,610.

To all whom it may concern:

Be it known that we, CLIFFORD F. RANDOLPH and CHARLES L. RICARDS, citizens of the United States, and residents of Plainfield, in the county of Union and State of New Jersey, have invented certain new and useful Improvements in Clamping Mechanisms for Radial Drills, of which the following is a specification.

10 This invention relates to radial drilling machines and particularly to the arm and saddle clamping mechanism therefor. In such machines is provided a vertical column on which is mounted a horizontal arm 15 slidably carrying thereon a drill spindle supporting saddle. The arm is normally adjustable in a horizontal plane about the vertical axis of the column and the saddle is adjustable along the arm. Power means 20 for clamping the arm against such movement about the column axis and means for clamping the saddle against movement along the arm is also provided. It is the primary object of this invention to provide 25 a single means for controlling the said power means and operating the saddle clamping means to perform both clamping operations.

Another object of the invention is to provide 30 clamping mechanism of the above type and means for either performing both clamping operations together by a single controlling means or independently controlling either clamping means to perform 35 its clamping operation independently of the other.

A further and more specific object of the invention is to provide in a radial drill of the above type, electrically operated clamping 40 means for clamping the arm against movement, a switch for controlling the said means, means for clamping the saddle against movement on the arm and a single means for controlling the said switch and 45 operating the saddle clamping means to perform both clamping operations.

With the above and other objects in view, our invention consists in the features of construction and operation set forth in 50 the following specification and illustrated in the accompanying drawing. In such drawing annexed hereto and forming a part of this specification, we have shown our invention embodied in a preferred form of

radial drilling machine but it will be understood that the invention can be otherwise embodied and that the drawing is not to be construed as defining or limiting the scope of the invention, the claims appended to this specification being relied upon for that purpose.

Referring to the figures of the drawing: Figure 1 is an elevation of a radial drill showing our improvements applied thereto.

Fig. 2 is an enlarged partial front view 65 of the drill spindle supporting saddle and arm.

Fig. 3 is an enlarged view through the arm on line 3—3 of Fig. 1, certain of the improved mechanism being shown in section. 70

Fig. 4 is a detail view taken on line 4—4 of Fig. 3.

Fig. 5 is a detail view taken on line 5—5 of Fig. 3. 75

In the drawing accompanying this specification, we have illustrated our invention in connection with a radial drill of the type shown in a copending application, Serial No. 381,556 to W. T. Sears. In such 80 machine, the drill arm supporting column is rotatably mounted on the base of the machine and is adapted to be clamped against rotation by means of an electric motor. In the drawing illustrative of our invention, 85 such a motor is shown for clamping the column against rotation and means is provided for securing the saddle against movement along the arm. A common means is provided on the saddle for controlling the 90 motor and operating the saddle clamp. Means is also provided whereby these clamping operations may be performed independently when such operation is desired. It will be understood that the details shown 95 in the drawing are illustrative of the invention which is capable of being embodied in various forms in other types of radial drills.

Referring more specifically to the drawing by reference characters, 1 indicates the base of the drilling machine supported on a bed 2. Mounted on the base for movement about a vertical axis is a column 3. Preferably this column is divided or formed 100 in two parts as shown in Patent No. 1,071, 590, dated August 26th, 1913. Supported 105 on the column and vertically adjustable

with respect thereto is a horizontal arm 4 along which is slidably a saddle 5 carrying a head provided with a rotatable drill spindle 6. Preferably the arm 4 or a carrying member therefor extends through the column between the two parts thereof and directly supports a gear casing 7 and an electric motor 8. From the motor 8 power is transmitted through gearing in the casing 7 to the main power shaft 9 extending longitudinally of the arm and thence to the spindle 6. The mechanisms thus far described do not of themselves constitute any part of the present invention and they can 15 be considerably modified as required.

The column 3 preferably is provided with an extension 10 which projects downward into the base parts 2 and 1. For carrying the weight of the column and associated parts during turning movement, we provide a series of centrally disposed devices. As illustrated, there is an anti-friction column support in the form of a ball thrust bearing 11 resting upon a plate 12. Engaging the top race of the ball bearing is a vertical tube 13, this tube extending through a central aperture in the projection 10 and being freely movable therein. Supported on the top of the tube 13 is a coil spring 14 and this coil spring in turn supports a second vertical tube 15. The tube 15 at its top engages a bushing 16 which has threaded engagement with the column. The spring 14 is sufficiently powerful to carry the entire weight of the column and associated parts when the clamping mechanism is released. The bottom of the column 3 is provided with a horizontal surface 17 adapted under certain conditions to engage a horizontal surface 18 on the top of the base section 2. In assembling, the surfaces 17 and 18 will be initially in contact. The bushing 16 is then turned so as to transfer the weight of 45 of the column from the base 2 to the vertical tube 15 and thence to the spring 14 and the ball bearing 11. The column is thus supported with the surfaces 17 and 18 entirely out of engagement. With the surfaces 17 and 18 out of engagement and with the weight of the parts substantially balanced on the bearing 11, it is possible to swing the column and arm very easily. After the arm has been swung to the desired position, the column is clamped by the mechanism now to be described. The clamping mechanism is vertically acting, viz., applies pressure to the column downward in opposition to the spring, thus forcing the surface 17 into a direct clamping engagement with the surface 18.

Carried by the extension 10 near the bottom thereof is a ring 19 having a downwardly and outwardly inclined upper surface. The base section 2 is provided with

an inwardly extending flange 20 having a horizontal bottom surface positioned immediately above the top surface of the ring 19. Interposed between the ring 19 and the flange 20 is a split ring 21 having bottom and top surfaces adapted respectively to engage the top surface of the ring 19 and the bottom surface of the flange 20. The ring 21 carries two apertured ears through which extends a threaded rod 22. At one end the rod 22 is engaged by a threaded handle 23 and at the other end is engaged by a threaded sleeve 24, this sleeve being adapted to be operated by a clamping motor 25 as shown in the drawing. The split clamping ring can therefore be operated either by hand or by power means, the latter operating through a worm 26 and worm wheel 27 secured to the said sleeve 24. This mechanism of itself is not a part of this invention and therefore will not be further described herein. Such mechanism is however defined in detail in the above cited application.

The motor 25 is controlled by a reversing drum switch 28 as shown in Fig. 3. The switch is rotated from a bevel gear 29 through mechanism to be hereinafter described. Contact of the terminals 30 and 31 by means of the pole 31' is adapted to operate the motor in a clamping direction, and contact of the terminals 30 and 32 by means of the pole 32' is adapted to operate the motor in an unclamping direction.

The means for clamping the saddle 5 to the arm 4 will now be described. A clamping shoe 33 engages a shoulder 34 on the arm 4. This shoe is supported by a threaded rod 35 extending through the saddle and having threaded to the front end thereof a nut or sleeve 36. The rod is also provided with an extended portion 37 having a hand lever 38 secured to the outer end thereof. The sleeve 36 is adapted to be rotatably operated to clamp or unclamp the saddle by means of a gear 39, such gear having a loose clutch connection with the sleeve as shown in Fig. 5. The sleeve is provided with two diametrically opposite lugs 40 adapted to be engaged by two similar lugs 41 on the gear 39. The purpose of this loose connection is hereinafter described.

Both the clamping motor switch 28 and the gear 39 are adapted to be operated from a single controlling lever 42 mounted on the saddle 5. As shown in Fig. 3, the following comprises the operative connection from the lever 42 to the said elements; lever 42, shaft 43, bevel gears 44, vertical shaft 45, bevel gear 46 engaging bevel gear teeth 39^a on gear 39, spur gear teeth 39^b on gear 39 engaging spur gear 47 on shaft 48, and a bevel gear 49 on shaft 48 meshing with the aforementioned switch bevel gear 29.

- In the drawing, the switch 28 and its operating mechanism are shown in the neutral position. These elements are normally held in such position by means of a spring 50 coiled about the shaft 43 and having the ends thereof engaging opposite sides of a lug 51 on the gear casing 52. An arm 53 secured to the shaft 43 is provided with a pin 54 extending between the said spring 10 ends. It will be seen that movement of the lever 42 and arm 53 in either direction will be against the action of the spring which will always tend to bring such elements back to the neutral position.
- 15 Considering both clamping mechanisms to be in the unclamped position, the operation of the mechanism is as follows. To operate both clamping mechanisms to secure the arm and column against movement on the base 20 and the saddle against movement on the arm, the operator moves the lever 42 to the right (Figs. 1 and 2). Such operation, through the connections described, rotates the switch 28 to make a clamping contact 25 at 30, 31 whereby the motor is rotated in a direction to clamp the column, and rotates the gear 39 to the right which, through the connection shown in Fig. 5 rotates the sleeve 36 to draw the shoe 33 into clamping contact with the arm 4. The operator now releases the lever 42 which, through the spring 30 50, is returned to a neutral position, the switch 28 also returning to a neutral or open position, as has been described. Be- 35 cause of the loose connection shown in Fig. 5, however, the gear 39 is permitted this backward rotation without rotating the clamping sleeve 36. The arm clamp is therefore left in its clamping position. When 40 it is desired to release the clamps, the lever 42 is swung to the left. Such operation rotates the sleeve 36 to the left to unclamp the saddle and contacts the switch at 32 whereby the motor 25 is rotated in the unclamping 45 direction. The operator now releases the lever 42 which goes back to a neutral position, as also does the switch 28. Because of the loose connection shown in Fig. 5, however, the sleeve 36 remains in its unclamp- 50 ing position.
- It may sometimes be desired to operate the arm clamp without operating the saddle clamp or vice versa. Such operations may be performed as follows: it will be noted 55 that the lever 38 may occupy either of two positions 55 or 56 (Figs. 1 and 2). When in the position 56, as illustrated, the screw rod 35 is so adjusted in the nut 36 that rotation of the nut in the clamping opera- 60 tion just described serves to clamp or unclamp the saddle along with the clamping or unclamping of the arm. If it is desired to clamp the arm without clamping the saddle, the lever 38 is moved to the posi- 65 tion 55. Such rotation thereof so adjusts the screw 35 in the nut 36 and releases the shoe 33 that the rotation of the nut 36 in the usual clamping operation is insufficient to effect clamping of the saddle. When so adjusted, the lever 42 may be used to operate the switch 28 to clamp or release the arm without effecting clamping of the saddle. The saddle may be clamped independently of the arm by the use of the lever 38.
- What we claim is:
1. In a drilling machine, the combination of a base, a column supported thereon, an arm mounted on the column, projecting horizontally therefrom and normally adjustable about the column axis, a spindle supporting saddle carried by and adjustable along the arm, means including electrically operated means for clamping the arm against movement about the column axis and the saddle against movement along the arm, a switch 80 for controlling the electrically operated means, a hand lever for controlling the switch and both said clamping operations, movement of the lever in one direction being adapted to perform the clamping operations 85 and movement thereof in the opposite direction being adapted to perform the unclamping operations, and means normally holding the switch and lever in a neutral position with the said clamping means in either an arm and saddle clamping or unclamping position.
  2. In a drilling machine, the combination of a base, a column supported thereon, an arm mounted on the column, projecting horizontally therefrom and normally adjustable about the column axis, a spindle supporting saddle carried by and adjustable along the arm, means for clamping the arm against movement about the column axis, means for 100 clamping the saddle against movement along the arm, and means for controlling both said clamping means from a single source to perform both clamping operations together or for independently controlling either 105 clamping means to perform its clamping operation independently of the other.
  3. In a drilling machine, the combination of a base, a column supported thereon, an arm mounted on the column, projecting horizontally therefrom and normally adjustable about the column axis, a spindle supporting saddle carried by and adjustable along the arm, means for clamping the arm against movement about the column axis, 110 means for clamping the saddle against movement along the arm, and means for controlling both said clamping means from a single source to perform both clamping operations together, the said controlling means 115 also being optionally operative on the first clamping means to clamp the arm without clamping the saddle.
  4. In a drilling machine, the combination of a base, a column supported thereon, an 120

arm mounted on the column, projecting horizontally therefrom and normally adjustable about the column axis, a spindle supporting saddle carried by and adjustable 5 along the arm, means for clamping the arm against movement about the column axis, means for clamping the saddle against movement along the arm, means for controlling both said clamping means from a single 10 source to perform both clamping operations together, and means for operating the saddle clamp without operating the arm clamping means.

5. In a drilling machine, the combination 15 of a base, a column supported thereon, an arm mounted on the column, projecting horizontally therefrom and normally adjustable about the column axis, a spindle supporting saddle carried by and adjustable 20 along the arm, means for clamping the arm against movement about the column axis, means comprising a screw and a nut threaded thereon for clamping the saddle against movement along the arm, means for 25 rotating one of such elements to effect clamping of the saddle to the arm and to simultaneously effect the clamping of the arm, and means for rotating the other element to independently effect clamping of the 30 saddle.

6. In a drilling machine, the combination 35 of a base, a column supported thereon, an arm mounted on the column, projecting horizontally therefrom and normally adjustable about the column axis, a spindle supporting saddle carried by and adjustable 40 along the arm, means for clamping the arm against movement about the column axis, means comprising a screw and a nut threaded thereon for clamping the saddle against movement along the arm, means for 45 relatively rotating the screw and nut to effect clamping of the saddle to the arm and to simultaneously effect the clamping of the arm, and means for relatively adjusting the screw and nut to place the saddle clamping means in either an operative or an inoperative position.

7. In a drilling machine, the combination 50 of a base, a column supported thereon, an arm mounted on the column, projecting horizontally therefrom and normally adjustable about the column axis, a spindle supporting saddle carried by and adjustable 55 along the arm, means for clamping the arm against movement about the column axis, means comprising a screw and a nut threaded thereon for clamping the saddle against movement along the arm, means for 60 rotating the nut to effect clamping of the saddle to the arm and to simultaneously effect the clamping of the arm, and means for relatively adjusting the screw to place the saddle clamping means in either an operative or an inoperative position.

8. In a drilling machine, the combination of a base, a column supported thereon, an arm mounted on the column, projecting horizontally therefrom and normally adjustable about the column axis, a spindle 70 supporting saddle carried by and adjustable along the arm, electrically operated means for clamping the arm against movement about the column axis, a switch for controlling such means, means for clamping 75 the saddle against movement along the arm, and a single hand operated means for controlling the said switch and operating the saddle clamping means to perform both clamping operations. 80

9. In a drilling machine, the combination of a base, a column supported thereon, an arm mounted on the column, projecting horizontally therefrom and normally adjustable about the column axis, a spindle 85 supporting saddle carried by and adjustable along the arm, electrically operated means for clamping the arm against movement about the column axis, a switch for controlling such means, means for clamping 90 the saddle against movement along the arm, a single hand operated means for controlling the said switch and operating the saddle clamping means to perform both clamping operations, and means permitting 95 the return of the switch to an open position without effecting the position of the saddle clamp.

10. In a drilling machine, the combination of a base, a column supported thereon, an arm mounted on the column, projecting horizontally therefrom and normally adjustable about the column axis, a spindle supporting saddle carried by and adjustable along the arm, electrically operated means for clamping 100 the arm against movement about the column axis, a switch for controlling such means, means for clamping the saddle against movement along the arm, a single hand operated means for controlling the said switch and operating the saddle clamping means to perform both clamping operations, and a lost motion connection between the 105 said hand operated means and the saddle clamping means whereby the switch and handle may be returned to a neutral position 110 without effecting the position of the saddle clamp.

11. In a drilling machine, the combination of a base, a column supported thereon, an arm mounted on the column, projecting horizontally therefrom and normally adjustable about the column axis, a spindle supporting saddle carried by and adjustable along the arm, electrically operated means for clamping 115 the arm against movement about the column axis, a switch for controlling such means, means for clamping the saddle against movement along the arm, a single hand operated means for controlling the said 120 switch and operating the saddle clamping means to perform both clamping operations, and a lost motion connection between the said hand operated means and the saddle clamping means whereby the switch and handle may be returned to a neutral position 125 without effecting the position of the saddle clamp. 130

switch and operating the saddle clamping means to perform both clamping operations, and means whereby either the switch or saddle clamp may be operated independently of 5 the other.

12. In a drilling machine, the combination of a base, a column supported thereon, an arm mounted on the column, projecting horizontally therefrom and normally adjustable 10 about the column axis, a spindle supporting saddle carried by and adjustable along the arm, power means for clamping the arm against movement about the column axis, means for clamping the saddle against 15 movement along the arm, and a single hand means for controlling both said clamping operations.

13. In a drilling machine, the combination of a base, a column rotatably supported 20 thereon, an arm mounted on the column and projecting horizontally therefrom, a spindle supporting saddle carried by and adjustable along the arm, power means for clamping the column against rotation on the base,

means for clamping the saddle against movement along the arm, and a single hand operated means for controlling the power means and operating the saddle clamping means to perform both clamping operations. 25

14. In a drilling machine, the combination of a base, a column rotatably supported thereon, an arm mounted on the column and projecting horizontally therefrom, a spindle supporting saddle carried by and adjustable 30 along the arm, means for clamping the column against rotation on the base, an electric motor for operating such means, a switch for controlling the motor, means for clamping the saddle against movement along the arm, and a single hand operated means on 35 the saddle for controlling the said switch and operating the saddle clamping means to perform both clamping operations. 40

In testimony whereof, we hereto affix our signatures.

CLIFFORD F. RANDOLPH.
CHARLES L. RICARDS.
